(57) **CLAIM**

The ornamental design for a smart watch, as shown and described.

DESCRIPTION

FIG. 1 is a front, right, top perspective view of a smart watch showing our new design;

FIG. 2 is a back, right, bottom perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof;

FIG. 8 is an enlarged bottom view thereof;

FIG. 9 is an enlarged detail view of a portion of the smart watch shown in area 9 in FIG. 1;

FIG. 10 is an enlarged detail view of a portion of the smart watch shown in area 10 in FIG. 2;

FIG. 11 is an enlarged detail view of a portion of the smart watch shown in area 11 in FIG. 3; and,

FIG. 12 is an enlarged detail view of a portion of the smart watch shown in area 12 in FIG. 4.

The evenly-dashed broken lines in the figures depict portions of the smart watch that form no part of the claimed design. The dot-dash broken lines encircling portions of the

(Continued)

smart watch in FIGS. 1, 2, 3, and 4 and illustrated in enlarged views in FIGS. 9, 10, 11, and 12 form no part of the claimed design.
